MAGAZINE EXCHANGING DEVICE FOR TYPOGRAPHICAL MACHINES

Filed Feb. 17, 1934

2 Sheets-Sheet 2

A technical drawing showing a cross-section of a component. The drawing is labeled 'Fig. 6.' in a cursive script. The component consists of a base plate with a central vertical rib. The rib has a top flange with a thickness of 23, a middle section with a thickness of 30, and a bottom section with a thickness of 30. The base plate has a thickness of 23. Various dimensions are labeled: 23, 30, 30, 33, 34, 36, 39, 45, and 49. The drawing uses hatching to distinguish between different parts of the component.

MAGAZINE EXCHANGING DEVICE FOR
TYPOGRAPHICAL MACHINESHerman R. Freund, Brooklyn, N. Y., assignor to
Intertype Corporation, Brooklyn, N. Y., a cor-
poration of New York

Application February 17, 1934, Serial No. 711,758

15 Claims. (Cl. 199—45)

The present invention relates to improvements in typographical machines of the well-known class shown and described generally in U. S. Patent No. 436,532 granted September 16, 1890 wherein character bearing matrices stored in a magazine are delivered therefrom under the control of a keyboard and assembled in lines from which type bars or slugs are cast, after which the matrix lines are returned to their appropriate channels in the magazine by distributing mechanism.

The invention is directed more especially to improvements in typographical machines of this class in which one or several of the matrix magazines are removably mounted in the machine to permit the substitution therefor of other magazines carrying different fonts of matrices from which it may be desired to compose matrix lines. More particularly, the invention relates to improvements for facilitating the removal and replacement of any one of a plurality of matrix magazines arranged in column-like fashion, each on a supporting frame mounted in the machine, each magazine, according to the present invention, being movable relatively to its frame without disturbing the other magazines or frames, removal and replacement of a magazine being capable of accomplishment by merely moving the magazine to be exchanged endwise substantially in its own plane.

The primary object of the invention is to provide means which will so facilitate the exchanging of magazines that the effort and labor required will be much less than heretofore required, the magazine exchanging operation will require less time, and damage to the magazines or the machine or injury to the attendant will be less likely to occur than heretofore. It will be understood that the magazines and their contained matrices, as used in machines of this class, are relatively heavy, a full standard size magazine weighing about one hundred pounds and a full "split" magazine, as the half-length magazines are commonly called, weighing sixty pounds or more. Consequently, the exchanging of magazines is a task which, apart from requiring the expenditure of much muscular effort by the attendant, is accompanied by the risk of slipping of the heavy magazine while being handled and thereby causing damage to the magazine or to the machine, and sometimes also to the attendant.

Devices have been previously proposed for aiding in the exchanging of magazines on machines of this class, but such devices are objectionable

not only because they require additional operations by the attendant preparatory to removal of the magazine, but they also require handling and manipulation of the magazine itself to withdraw it to a position clear of the magazine column where it is entirely free to be lifted and carried away. In other words, the previously proposed devices referred to provide no mechanical facility for actually performing the magazine removal and replacement operations whereby any one of the magazines of a column will be moved from its supporting frame endwise clear out of the column, or a magazine will be carried from a position outside of the column endwise into the column to its normal resting place or operative position on any one of the usual magazine supporting frames.

Respecting such previously proposed devices, it may also be said that two types of magazines have been used, one of which types of magazines has the well-known matrix escapements attached thereto and the other of which types of magazines is engageable with matrix escapements which are separate from the magazine and attached to the machine or to the magazine supporting frame. In order to enable endwise removal of the latter type of magazine without disturbing the other magazines in the column, it is obviously necessary to first clear the path through which the magazine is to be withdrawn by removing the cooperating matrix escapements from said path, an operation which of course is not required with the former type of magazine having the escapements permanently attached to it. For the purpose of removing the obstructing escapements from the path of removal of a magazine having the escapements mounted separately therefrom, it has been proposed to mount the escapements on the magazine supporting frame and slide the latter forwardly in the column, together with the magazine, to an extent just sufficient to bring the escapements clear of any obstruction below them, whereby the escapements will be free to be dropped away from engagement with the magazine. Such a special arrangement however fails to accomplish the desired object of the present invention since, like other previously proposed devices, it merely provides an operation which is preparatory to the actual exchanging of the magazine, leaving to the attendant the work of manually manipulating the magazine itself out of and into the column.

The present invention proposes to overcome the foregoing objections and shortcomings of previously proposed devices, and to this end it provides

mechanical means in the form of sliding arms for disengaging a magazine from the inclined supporting frame upon which it normally rests, sustaining the lower end of the magazine above said supporting frame while the magazine gravitates substantially in its own plane out of and clear of the column, and then supporting the magazine in a projected position in front of the column and at a conveniently low level where it may be lifted freely off the arms without encountering obstructions or disturbing any other magazines or associated parts of the machine. Thus the work of the attendant required in the exchanging of a magazine is much less than that heretofore required, since the act of manually manipulating the magazine itself out of and into the column of magazines is no longer necessary, and magazine changes can be made in considerably less time and with a minimum risk of damage or injury.

To these and other ends, the invention consists in certain improvements and combinations and arrangements of parts all as will be hereinafter more fully described, the features of novelty being pointed out more particularly in the claims at the end of this specification.

In the accompanying drawings:

Figure 1 is a side elevation of a portion of a typographical machine embodying the present invention;

Figure 2 is a side elevation, partly in section, of a portion of the structure shown in Figure 1, illustrating a detail of the means for shifting the column of magazines.

Figure 3 is a detail perspective view of a part of the magazine column shifting means;

Figure 4 is a view, partly in section, of the structure shown in Figure 1 as viewed from above.

Figure 5 is a partial vertical section taken on the line 5—5 in Figure 4; and

Figure 6 is a detail vertical section taken on the line 6—6 in Figure 4.

Similar parts are designated by the same reference characters in the different figures.

The preferred embodiment of the invention is shown in the present instance applied to a typographical machine of the general class disclosed in the patent hereinbefore mentioned, and more particularly to a machine of this class provided with a shiftable column of matrix magazines substantially as disclosed in U. S. Letters Patent No. 1,650,552 granted November 22, 1927 and adapted to contain the common form of "split" or half-length magazines, an example of which is disclosed in U. S. Letters Patent No. 1,338,627 granted April 27, 1920. It is to be understood however that the invention is not limited to such particular form of magazine column shifting means or such particular construction of the magazines since other forms of column shifting means and magazines may be used, and that the invention is not restricted to the specific embodiment thereof shown since equivalent constructions are contemplated and such will be included within the scope of the claims.

In the present instance, the invention is shown applied to a machine adapted to contain a column of three magazines 1, 2 and 3 arranged in superposed relation, these magazines being of the "split" or half-length form and having complementary matrix conducting sections 4, 5 and 6 respectively to cooperate with their upper ends and direct the matrices thereto from the usual matrix distributor in the machine, the usual channel entrance 7 leading from the distributor for directing the matrices into the magazine conducting section

4, 5 or 6, according to which of the magazines is in operative position, being shown in Figure 1. The usual assembler throat or entrance 8, which is adapted to receive matrices from the magazine 1, 2 or 3, according to which of these magazines is in operative position, serves to direct the matrices in the usual way to the well-known assembling means in the machine, and the usual keyboard actuated escapement operating reeds 9, mounted in a stationary part of the main frame 10 serve to actuate the escapements for the magazine in operative position and thereby effect the delivery of matrices therefrom.

The magazines 1, 2 and 3 and their cooperating matrix conducting sections 4, 5 and 6, respectively, according to the present invention, are mounted on the magazine supporting frames 11, 12 and 13. These frames are arranged one above the other in suitably spaced relation and are rigidly secured together by suitable brackets 14 and 15 which are secured to the sides of said frames near their upper and lower ends. The bottom frame 13 rests, by means of a roller 16 at each side thereof, upon a track 17, one of these tracks being provided at each side of the machine upon side cheeks 18 which are fixed to or constitute part of the main frame of the machine. Each of the side cheeks 18 is provided with a track embodying a toothed rack 19 along which a pinion 20 may travel, the pinion being fixed to a shaft 21 having a handle 22 fixed thereto so that turning of said handle will rotate the pinion and thereby cause it to travel along its toothed rack. The pinion shaft 21 at each side of the machine is connected by a link 22^a to the shaft 22^b on which the roller 16 at the respective side of the machine is mounted in the frame 13. The magazine shifting means as thus far described is similar to that disclosed in patent No. 1,650,552 above noted, the magazines being shifted by turning the handle 22 whereby they are carried along the tracks 17 and 19 to bring one or another magazine into operative relation with the channel entrance 7 and assembler throat 8, and to bring the escapements 23, 24 or 25 of the magazine brought into operative position, into cooperative relation with the escapement actuating reeds 9, in the manner described in detail in said Patent No. 1,650,552.

When, as shown, "split" magazines are employed, only these magazines or lower sections 1, 2 and 3 require removal and replacement to bring different matrix fonts into use, since such "split" magazines are employed to contain matrix fonts comprising only enough matrices to fill the short magazine or lower section, the upper sections 4, 5 and 6 serving merely as conductors, or in effect, as extensions of the channel entrance 7 for leading matrices from the distributor to their respective storage channels in the lower magazines or sections 1, 2 and 3. The lower magazines or sections 1, 2 and 3 may be of the ordinary construction each comprising top and bottom channel plates 26 and 26' rigidly secured together by spacing bars 27 at the sides and reinforced by suitable stiffening bars 28, 29 and 30 secured to and extending transversely across their under sides, and a central longitudinal bar 31 secured to its under side and arranged to slide in a longitudinal guide groove 32 in the respective magazine supporting frame.

The means provided by the present invention for facilitating removal of any one of the lower magazine sections from its supporting frame out of and clear of the column comprises a pair of rods 33, one near each side of the respective sup-

porting frame and slideable thereon, these rods being of substantially the full length of the respective supporting frame and being retained thereon against sliding forwardly by abutment shoulders 34 secured on their under sides and engageable with fixed abutment lugs 34' on the supporting frame, as shown in Figure 6, the abutment plates 34 on the rods 33 being disengageable from the abutment lugs 34', by lifting the forward ends of said rods, the latter being then released so that they may slide forwardly. Each of the magazine supporting frames is provided at the sides thereof with plates 36 which are fastened thereto by screws or other suitable means and form continuous surfaces level with the top face of the sides of the supporting frame, these plates being sufficiently wide for a portion of their length to overlie part of the width of the respective rods 33. As indicated with respect to the uppermost magazine as shown in Figure 5, the rods 33 normally rest on the respective supporting frame below and out of contact with the magazine, the transverse bars 28, 29 and 30 of the magazine resting on the magazine supporting frame 11, as shown. The rods 33 toward their forward ends are reduced in vertical thickness over a portion of their width corresponding to the width of the portions of the plates 35 which overlie them, such reduced thickness of the rods being indicated at 36, and the rest of the width of these rods is of increased thickness, as indicated at 37, over a length just beyond the normal position of the uppermost transverse magazine bar 28. A pair of upwardly extending pins or projections 38 and 39 are provided on the higher or thicker portions 37 of the bars 33, the pin 38 being located adjacent to the top edge of the transverse magazine bar 28 and the pin 39 being located adjacent to the bottom edge of the transverse magazine bar 29, the distance between the pins 38 and 39 being slightly greater than the distance between the respective adjacent faces of the bars 28 and 29 so that said transverse bars may be lowered into position between said pins or lifted from such position. The bars 33 are provided at their upper ends with lugs or raised portions 40 the forward edges of which form shoulders 41.

From the foregoing and as clearly shown with respect to the lower magazine section 1 in Figure 5, the bars 33 are retained in the respective magazine supporting frame by engagement of the abutment plates 35 thereon with the lugs 34' fixed to the respective supporting frame, and the lower magazine section, while firmly seated on its respective supporting frame, is retained against longitudinal displacement on its supporting frame by the engagement of the pins 39 on the bars 33 with the cross member 29 on the lower magazine section, the latter being thereby retained against sliding forwardly due to its forwardly and downwardly inclined position in the machine. Since the bars 33 lie on the respective supporting frame out of contact with the magazine resting on said frame, lifting of the lower or forward ends of these bars will rock them about their rearmost point of support 42 on the respective supporting frame until the foremost portions of their raised surfaces 37 contact with the foremost transverse bar 30 of the respective lower magazine section, and continued lifting or rocking movement of the bars 33 will result in disengagement of the abutment plates 34 on these bars 33 from the abutment lugs 34' on the respective supporting frame, the bars 33 and the respective magazine being then free to gravitate forwardly.

During the forward gravitating movement of the magazine, it will be supported at its forward end by the transverse bar 30 resting on the bars 33 while the upper end of the magazine will rest and slide on the respective magazine supporting frame until it passes off the forward end thereof, and when the bars 33 have reached the limits of their forward movement, as determined by the engagement of the shoulders 41 of the lugs 34' thereon against the upper ends of the plates 35 on the respective supporting frame, the magazine will rest on the bars 33 in a position clear of the magazine column; and the magazine thus removed from the column may be freely lifted from the projected bars on which it rests, as will be apparent with respect to the magazine 2 as shown in Figure 5. It will be understood that the space between the top of a magazine and the underside of the supporting frame immediately above it is limited so that the bars 33 cannot be rocked or lifted to a sufficient height to bring their raised surfaces 37 into contact with the transverse bars 28 and 29 on the magazine, and this arrangement is advantageous since it renders unnecessary lifting of the entire weight of the magazine by the bars 33 when the latter are lifted or rocked upwardly for release.

When a magazine has gravitated forwardly out of the column into the position shown with respect to the lowermost magazine 3 in Figure 1 or the middle magazine 2 in Figure 5, the bars 33 sustain the magazine in such extended position, in cooperation with the plates 35 on the respective supporting frame, at a lower level in the inclined plane of the column of magazines, and it will be appreciated by those familiar with machines of this class that the magazine, while occupying this position, can be most conveniently handled since it can be lifted off the extended bars 33 entirely free of obstructions. Means is preferably provided for facilitating the placing of a substitute magazine on the extended rods 33, such means as shown in the present instance comprising a cross-tie or brace 43 which rigidly connects the rods 33 at their forward ends, the cross-tie or brace 43 having a recess 44 therein which is in alinement with and corresponds in shape with the longitudinal guide groove 32 in the magazine supporting frame, the recess 44 in the cross-tie being thus adapted to receive the longitudinal bar 31 on a magazine. The cross-tie or brace 43 also serves as convenient means for raising the forward ends of the bars 33 simultaneously. When placing a substitute magazine on the extended bars 33, the recess 44 in the cross-tie 43 receives the longitudinal bar on the magazine and thereby locates or centers it laterally while the pins 39 engage the cross-bar 29 on the magazine and thereby locate it longitudinally. After a magazine has been thus seated on the extended bars it is only necessary for the attendant to push against the lower end of the magazine and thereby slide it, together with the bars 33, into the magazine column until the abutment plates 34 on the bars 33 pass over and engage behind the retaining lugs 34' on the magazine supporting frame. Such movement of the substitute magazine into the column causes it to ride up on to the respective supporting frame or the plates 35 forming portions thereof, thereby lifting the magazine above or out of contact with the bars 33 so that the cross bars on the magazine all rest on the supporting frame and thereby support the magazine in operative position in the machine; the pins 39 on the bars 33 however remaining in

abutting relation with the cross bar 29 on the magazine and thereby preventing the latter from sliding forwardly out of its operative position. In order to facilitate the riding of the cross bars 5 of the magazine up on to the respective supporting frame while being moved into its operative position in the column, the forward end of each of the plates 35 may be bevelled, as indicated at 135.

10 As already hereinbefore stated, any one of the magazines may be brought into operative relation with the usual assembler throat 8 by the magazine shifting means shown, the operation of which is fully disclosed in said Patent No. 15 1,650,552. However, according to that patent, when the lowermost magazine is in operative relation with the assembler throat, forward removal of such magazine according to the means provided by the present invention, could not be 20 accomplished. Means is therefore provided by the present invention for moving the column of magazines to such position as will bring the lowermost magazine 3 above the assembler throat 8 to permit its removal from the column into 25 the position shown in Figure 1, the pinion 20 according to the present invention being reduced in diameter for a portion of its width excepting one of its teeth 120 which is left of full width, and a segmental seat 50 is mounted beyond the 30 forward end of the toothed rack 19 in the path of travel of the portion of the pinion of reduced diameter, the radius of the segmental seat conforming to that of the reduced diameter of the pinion, the travel of the pinion being increased 35 so that it may pass beyond the end of the toothed rack and be received in the seat 50. The increased forward travel of the pinion thus provided permits increased shifting of the magazine column in the forward direction, and since the 40 pinion is capable of continued rotation after its portion of reduced diameter has lodged in the segmental seat 50 until such rotation of the pinion is arrested by the engagement of the full width tooth 120 with the stop 50, the center of 45 the shaft 51 on which the forward portion of the magazine column rests and which is eccentric to the pinion shaft 21 may be brought by rotation of the handle 22 into a position where its center is located forwardly of a plane passing 50 vertically through the center of the pinion, as shown in Figure 2. Such free turning of the pinion after the magazine column has reached the limit of its forward shift, raises the forward end of the column, as shown in Figures 1 and 2 55 so that the bottom magazine 3 of the column, together with the slidable bars 33, may be extended forwardly above and clear of the assembler throat 8, thus permitting changing of the lowermost magazine in the column without obstruction 60 by the assembler throat. After the lowermost magazine has been exchanged, the magazine column may be lowered to bring this magazine into operative relation with the assembler throat 8 and the escapement actuating devices, 65 or to shift the magazine column to bring one of the upper magazines into such operative relation by turning the magazine shift handle 22. During the first part of the rotation of the pinion 20, the eccentric shaft 51 on which the forward end 70 of the magazine stack rests will turn with it, the pinion rotating in a clockwise direction (Fig. 2) in the segmental seat 50, until the full width tooth 120 engages in the first tooth gap 190 in the rack 19, whereupon further rotation of the 75 pinion in said direction will cause its teeth to

successively engage and travel rearwardly along the rack in the usual manner, it being understood that each time the eccentric shaft 51 reaches its lower position beneath the axis of the shaft 21, one of the magazines in the stack will be lowered into operative relation with the assembler throat 8 to deliver matrices thereto and its escapements will be in operative relation with the escapement actuating reeds 9, while the upper end of such magazine in operative 10 position will be in operative relation with the entrance channel 7 to receive matrices returning to such operative magazine from the distributor. The shifting means for the column of magazines, as herein shown, thus enables the lowermost magazine in the stack to be readily brought into a 15 position where the assembler throat and escapement actuating reeds will be clear of the path of such magazine while being removed by the bars 33 and another magazine substituted in the manner hereinbefore described. It will be understood of course that the upper magazine 1 or the middle magazine 2 may be removed and another substituted, without obstruction, when one of the magazines below it in the column is in operative 20 position.

I claim as my invention:—

1. In a typographical machine having a column of matrix magazines and frames for supporting the respective magazines thereon in operative 30 positions in the machine, means slidable on one of said supporting frames in substantially the plane thereof and operative to remove a magazine therefrom and sustain it in removed position clear of the column.

2. In a typographical machine having a magazine supporting frame therein and a matrix magazine supported in operative position on said frame, slidable means on said frame underlying the magazine thereon in a substantially parallel 40 plane but normally out of supporting relation therewith and movable into engagement with said magazine to slide it on said frame and thereby remove it therefrom and to sustain said magazine in removed position.

3. In a typographical machine having a magazine supporting frame therein and a matrix magazine resting slidably on said frame, slidable means on said frame normally supported thereon in substantially the plane thereof at a level below 50 and in non-supporting relation with the magazine thereon, and magazine engaging means on said slidable means rendering the latter operative by its sliding movement to slide the magazine on said frame endwise therefrom on to said slid- 55 able means to be supported thereby.

4. In a typographical machine having a frame therein and a matrix magazine slidably supported thereon for endwise movement, slidable means supported on said frame normally in non-sup- 60 porting relation with a magazine on said frame and having a coupling for connecting it to the magazine, said slidable means being operative to slide the magazine endwise on said frame to remove it therefrom and to receive and support the magazine when removed from said frame.

5. In a typographical machine having a frame therein and a matrix magazine supported thereon for endwise movement, slidable means supported on said frame in substantially the plane thereof 70 normally in non-supporting relation with a magazine thereon, said means being movable into engagement with such magazine to convey it endwise off said frame.

6. In a typographical machine having a frame 75

- therein for supporting a matrix magazine thereon normally in inclined working position in the machine, slidable means on said frame having means for sustaining the magazine in said inclined position, said slidable means being operative to convey the magazine from said frame and having means for supporting the magazine by its lower end while conveying it off said frame and being adapted to receive the magazine flatwise after it leaves said frame.
7. In a typographical machine having a frame therein for supporting a matrix magazine thereon in inclined position in the machine, slidable means supported on said frame normally in non-supporting relation with a magazine thereon and movable into engagement with the magazine to convey it off said frame, and means cooperative with said frame and slidable means for sustaining the magazine in inclined position and releasable by said movement of the slidable means into engagement with the magazine, said slidable means being operative, when released, to convey the magazine off said frame and to sustain it when removed from said frame.
8. In a typographical machine having a frame therein for supporting a magazine thereon for endwise movement, means supported to slide and rock with respect to said frame, said means normally occupying a position in non-supporting relation with a magazine on said frame and being rockable into supporting relation with such magazine and slidable to convey such magazine endwise off said frame and support it in an extended position wholly removed from said frame.
9. In a typographical machine having an inclined frame therein for supporting a magazine thereon for endwise movement, means supported to slide on said frame and also capable of being lifted at the forward end, and cooperative abutment means at the forward ends of said slidable means and frame for sustaining the magazine on said frame, said slidable means normally occupying a position in non-supporting relation with a magazine on said frame and being releasable by said abutment means when lifted to convey the magazine off said frame and to receive it after it leaves said frame.
10. In a typographical machine having a frame therein and a matrix magazine supported in operative position on said frame and movable thereon for removal endwise therefrom, slidable means on said frame operative to convey a magazine endwise therefrom in substantially its own plane, and means for sustaining the magazine flatwise in such removed position.

11. In a typographical machine having a column of matrix magazines and frames for supporting the respective magazines thereon in operative position in the machine, means slidable on each of said frames and operative to convey a magazine therefrom to a position clear of the column and to convey a magazine from said position into the column and on to said frame by movement of the magazine substantially in its own plane.

12. In a typographical machine having a magazine supporting frame therein and a matrix magazine having upper and lower sections supported on said frame, slidable means on said frame operative to slide the lower magazine section endwise into position on said frame to cooperate with the upper magazine section.

13. In a typographical machine having a column of matrix magazines each comprising upper and lower sections, slidable means operative to convey the lower section of a magazine endwise out of the column to the extent at least of its own length.

14. In a typographical machine having a main frame provided with matrix assembling means, a column of matrix magazines, and frames supporting the magazines shiftably to bring one or another thereof into operative relation with said matrix assembling means, each magazine being removable endwise from its supporting frame, rack and pinion means for shifting the column of magazines to bring one or another thereof into such operative relation, including means permitting operation of the pinion independently of the rack to bring the lowermost magazine of the column into a position above its operative position where its path of removal will be clear of the assembling means.

15. In a typographical machine having a main frame provided with matrix assembling means, a column of matrix magazines, and frames supporting the magazines shiftably to bring one or another thereof into operative relation with said assembling means, slidable means operative to convey a magazine endwise in substantially its own plane from its frame into a position clear of the column, and rack and pinion means for shifting the column of magazines, including means for supporting the pinion for rotation independently of the rack to bring the lowermost magazine of the column into a plane above the assembling means.

HERMAN R. FREUND.
